Patented Feb. 2, 1960

187,169

RESPIRATOR MASK OR THE LIKE

George H. Schauweker, Southbridge, Mass., assignor to American Optical Company, Southbridge, Mass., a voluntary association of Massachusetts

Application December 13, 1957, Serial No. 48,896

Term of patent 14 years

(Cl. D83—1)

Des. 187,169

PAGE 2

fig. 3

Fig.5

Fig. 1 is a top plan view of a respirator mask or the like, showing my new design, the straps being broken away for convenience of illustration;

Fig. 2 is a front elevational view thereof, the straps being broken away for convenience of illustration;

Fig. 3 is a right side elevational view thereof;

Fig. 4 is a rear elevational view thereof with the straps being broken away for convenience of illustration; and

Fig. 5 is a bottom plan view thereof with the straps being broken away for convenience of illustration.

The dominant features of the design are shown in full lines on the drawing.

I claim:

The ornamental design for a respirator mask or the like, substantially as shown and described.
